UNITED STATES PATENT OFFICE.

AUGUSTE E. CHARBONNEAUX, OF SAN FRANCISCO, CALIFORNIA.

EXPLOSIVE.

1,174,546.

Specification of Letters Patent.

Patented Mar. 7, 1916.

No Drawing.

Application filed January 14, 1914. Serial No. 812,031.

To all whom it may concern:

Be it known that I, AUGUSTE E. CHARBONNEAUX, a citizen of the United States, residing at San Francisco, in the county of San Francisco and State of California, have invented new and useful Improvements in Explosives, of which the following is a specification.

The object of the present invention is to provide an improved explosive.

In forming my improved explosive I take an oxidizable substance such as a nitrated hydrocarbon compound and mix it with the following oxidizing substances, namely, picric acid, barium nitrate, and lead peroxid.

The nature of the hydrocarbon compound will depend upon the use to which the explosive is to be put. To make an explosive for shells, I use nitro-naphthalene as the nitrated hydrocarbon compound. All four ingredients of the explosive are then in the form of powder and they are used in the following proportions by weight:—nitro-naphthalene two parts, picric acid four parts, barium nitrate ten parts and lead peroxid one part.

I may also use nitrated petroleum or nitrated oil of turpentine, the use of which in place of nitro-naphthalene results in a pasty mixture, which can easily be divided into small parts, and becomes dry in the course of time. Its combustion is slower than that of the first described compound, and it is suitable as an explosive for rifles.

Both forms of the explosive burn without smoke.

I claim:—

1. An explosive consisting of a nitrated hydrocarbon, picric acid, barium nitrate and lead peroxid.

2. An explosive comprising nitro-naphthalene, picric acid, barium nitrate, and lead peroxid.

In testimony whereof I have hereunto set my hand in the presence of two subscribing witnesses.

AUGUSTE E. CHARBONNEAUX.

Witnesses:

FRANCIS M. WRIGHT,
D. B. RICHARDS.
